UNITED STATES PATENT OFFICE

2,441,836

RAPID START AND STOP CLUTCH MECHANISM FOR PHONOGRAFS

Theodore H. Nakken, New York, N. Y., assignor
to The Soundscriber Corporation, New Haven,
Conn., a corporation of Connecticut

Application June 19, 1944, Serial No. 540,929

2 Claims. (Cl. 274—1)

1

This invention relates to phonographs of the disk record type employing sound recording and sound reproducing apparatuses.

One object of this invention is to provide an improved start and stop mechanism for a phonograph turntable to permit the latter to be started and stopped with the minimum amount of lost motion, and without slowing-down or speeding-up periods which might give rise to changes in pitch.

A further object is to provide a start and stop mechanism of the above nature in which the clutch is mounted to connect the motor drive shaft with the turntable spindle, and is made quite compact so as to reduce the height of the machine.

A further object is to provide a device of the above nature which will be simple in construction, inexpensive to manufacture, easy to install and manipulate, ornamental in appearance, and very efficient, and durable in use.

With these and other objects in view, there has been illustrated on the accompanying drawings one form in which the invention may conveniently be embodied in practice.

In the drawings,

Fig. 1 is a side view of a clutch mechanism embodying the present invention.

Fig. 2 is a transverse sectional view of the same, taken along the line 22 of Fig. 1, looking downwardly in the direction of the arrows.

Fig. 3 is a sectional view of the same, on a larger scale, taken along the line 3—3 of Fig. 2.

Fig. 4 is a diagram showing the electrical circuit of the improved clutch mechanism.

This invention is an improvement over the invention disclosed in the United States Patent No. 2,240,320, of April 29, 1941, for "Quick start and stop mechanism for phonograph turntables," and U. S. Patent No. 2,278,680, of April 7, 1942, for "Quick start and stop drive mechanism for phonograph turntables," both of which patents were granted to Lincoln Thompson.

The present invention is of particular importance for use in a transcriber of a disk record type of dictating machine because it enables the record to be started and stopped with extreme rapidity and without stopping the motor, which runs continuously. It may also be used during the recording of dictation for rapidly starting and stopping the record and for simultaneously stopping the feed of the recording arm across the record.

Referring now to the drawings, wherein like reference numerals designate like parts through-

2

out the several views, the numeral 10 indicates the chassis of a dictating machine which is driven by a motor 46 (see Fig. 4) having a vertical shaft 11 which in turn drives a turntable 12 by means of a flexible clutch connection between the shaft 11 and a turntable spindle 13—the latter being mounted in a bearing 13a secured to the chassis 10 by a half flange 13b.

The motor 46 is mounted upon a plate 14 supported from the chassis 10 by means of four pillars 15, 16, 17, 18, said pillars being surrounded at their lower ends by rubber grommets 18a. Provision is also made of an electromagnet-supporting plate 19 made of iron which is suspended from the chassis 10 by means of a plurality of vibration reducing filters 20, each of which includes a spring and a snubber member.

Depending from the plate 14 are a pair of electromagnets which when energized attract an upper clutch plate 24, thus disengaging the clutch and thereby stopping the turntable driving spindle 13 substantially instantly, as will be herein-after more fully described.

Provision is made of a lower circular clutch plate 21 having an upper leather clutch surface 22, and a depending flywheel rim section 23 which serves to smooth out gear rumble due to any possible inaccuracies in the gear meshing. The plate 21 is secured as by a set screw 23a to the motor shaft 11.

The upper circular movable iron clutch plate 24 has a lower clutch surface 25 of leather and an upper annular ring 26 of cork for engaging a pair of iron cores 27 depending from the iron plate 19. The cork ring 26 on the upper clutch plate 24 serves to eliminate noise when said plate makes contact with the cores 27 of the electromagnets. The cores 27 are surrounded by a pair of electromagnetic coils 28, each of which has terminals 29 and 30 connected to any suitable source of direct current, such as an A. C. rectifier 45 (shown in Fig. 4).

The upper iron driven clutch plate 24 is flexibly mounted concentrically with the turntable spindle 13 and is adapted to be pressed into contact with the lower driving clutch plate 21 by means of an adjustable coiled spring 31 which presses downwardly upon said upper plate 24. The spring 31 is engaged at its upper end by a screw 50 collar member 31a having a knurled flange 31b, said collar member being adjustably mounted on a threaded bushing 31c secured to the spindle 13 as by a set screw 31d, as shown.

The upper clutch plate 24 is provided with a central aperture which is covered by a flexible

canvas membrane 33 secured to said upper clutch plate 24 by means of a plurality of outer rivets 34, said rivets having their upper heads seated upon an outer cover ring 35. The inner portion of the canvas coupling membrane 33 is secured to a central coupling stud 36, as by an inner cover ring 37 and inner rivets 38 and said stud 36 is screwed into a left hand threaded aperture in the bottom of the turntable spindle 13, thus providing for an extremely flexible universal coupling having vertical flexibility with a minimum of rotational flexibility. This fabric center coupling also serves as an effective filter for motor vibrations.

In order to stabilize and level the movable iron upper clutch plate 24 and complete the magnetic circuits through the iron plates 19 and 24, a pair of diametrically spaced additional iron studs 39, 39 are provided, which are located symmetrically between the pair of electromagnetic coils 28, 28.

The turntable 12 is rigidly secured to the spindle 13, as by a drive fit, and is embraced by a disk-supporting shell 40 having a depending exterior rim 41, said shell 40 resting upon a cork vibration filter ring 42 seated in an annular outer recess 42a in said turntable 12.

In order to feed the recording head 49 slowly across the record 48, the spindle 13 is provided with a short worm gear section 47 which engages with a worm (not shown) mounted on a connecting rod (not shown) drivingly connected with the recording head arm 50. This construction is fully described in the prior U. S. Patent No. 2,133,596, granted October 18, 1938, to Lincoln Thompson, entitled "Feed mechanism for disk recording machines."

Operation

It will be understood that when out of use, the upper and lower clutch plates 24 and 21 will be in abutment, as shown in Figs. 1 and 3. When the motor switch 44 and the manually-operated clutch switch 43 are closed, the clutch plates 21 and 24 will remain in abutment until the tubes of the rectifier 45 have warmed up sufficiently to energize the coils 28 with the rectified D. C. from the rectifier, which is supplied with power from line wires L₁ and L₂. The cores 27 of the electromagnets will then attract the upper clutch plate 24 and cause it to move away from the lower clutch plate 21, thus stopping the turntable 12. The motor 46, clutch plate 21, and shaft 11 will, of course, continue to run at full speed.

Whenever the electromagnetic coils 28 are thereafter deenergized by opening the normally closed clutch switch 43, the current will be shut off from the electromagnetic coils 28, and the spring 31 will cause the movable upper clutch plate 24 to jump downwardly toward the lower clutch plate 21 and away from the cores 27 of the electromagnets, and thus cause the turntable to start up substantially instantaneously.

To stop the turntable it will only be necessary to release the spring-actuated switch 43, allowing it to automatically close, energizing the coils 28 and causing the cores 27 to attract the upper clutch plate 24 away from the lower clutch plate 21, the cork ring 26 serving as a braking surface

to stop the rotation of the turntable substantially instantly.

It will be understood, of course, that while dictating whenever the turntable 12 and its spindle 13 stop rotating, by disengaging the clutch plates 21 and 24, the recording arm feed will also be stopped, thus avoiding waste of the recording space on the record.

It will be understood that during the upward and downward movements of the upper clutch plate, the shocks due to the engagements of said plate with the electromagnet cores 27 and the lower clutch plate 21, respectively, will be cushioned by the filters 20. Any tendency for the recording and reproducing needles to leave their proper grooves will thereby be eliminated.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new and for which it is desired to secure Letters Patent is:

1. In a clutch for rapidly starting and stopping a phonograph turntable having a spindle, an outwardly-extending disk secured to the lower end of said spindle, a continuously-rotated motor-driven shaft in alignment with and longitudinally spaced from said spindle, a lower clutch plate secured to said shaft, an upper iron clutch plate having a central aperture concentric with said disk, a flexible membrane, means clamping portions of said membrane to said upper clutch plate and said disk, respectively, whereby said upper clutch plate is flexibly connected with said spindle, spring means for normally holding said iron clutch plate in engagement with said lower clutch plate, and manually-controlled electromagnetic means for attracting said iron clutch plate to move it away from said lower clutch plate against the action of said spring to stop the rotation of said turntable spindle.

2. A clutch as defined in claim 1, in which said electromagnetic means includes a plurality of electromagnets located above said iron clutch plate, and a manually-controlled switch for opening and closing the circuit through said electromagnets.
